BEAM CONNECTION FOR PRECAST
CONCRETE MEMBERS

Albert Henderson, Pittsburgh, Pa., assignor, by
mesne assignments, to Peoples First National
Bank & Trust Company, Pittsburgh, Pa., a na-
tional banking association

Application February 27, 1946, Serial No. 650,495

1 Claim. (Cl. 72—108)

1

This invention relates to a building construction composed of precast reinforced concrete members and, in particular, to a connection between a beam thereof and a supporting member such as a column.

In building structures composed of precast concrete members, it is frequently necessary to provide a supporting member, such as a column, with a bracket secured thereto for supporting a beam or girder. If the beam or girder simply rests on the upper face of the bracket, it develops a tension in the upper portion of the bracket tending to pull it away from the supporting column. The bracket must, therefore, be specially reinforced and secured to the column by a connection of exceedingly great strength. I have invented a novel form of connection between a beam or girder, the bracket which supports it and the column to which the bracket is secured, whereby the aforementioned force is eliminated and a compression force is developed instead, tending to hold the upper portion of the bracket in abutment with the supporting column. In a preferred embodiment of the invention, I provide a precast reinforced concrete beam or girder having upper and lower longitudinal bars embedded therein. A securing member such as a length of angle bar is disposed transversely at the ends of the girder and is welded to the upper reinforcing bars thereof. The angle bar is secured to the reinforcing bars embedded in the column. The column has a bracket secured thereto on which the girder rests. A connection is provided between the girder and bracket which tends to develop compression in the bracket on deflection of the girder under load.

A complete understanding of the invention may be obtained from the following detailed description which refers to the accompanying drawings illustrating a preferred embodiment and modifications thereof. In the drawings,

Figure 1 is a partial side elevation of a column having a bracket secured thereto and a girder mounted thereon and attached to the column and bracket;

Figure 2 is a similar view showing a modified form of construction; and

Figure 3 is a similar view showing a further modified form.

Referring in detail to the drawings, a precast reinforced concrete column 10 has longitudinal reinforcing bars 11 embedded therein connected by transverse reinforcing rods 12 welded thereto. The column is preferably rectangular in section and the bars 11 are located adjacent

2

the corners thereof. The rods 12 extend around the bars 11. A precast reinforced concrete bracket 13 is secured to one side of the column. The bracket has reinforcing bars 14 embedded therein, the ends of which are welded to pipe lengths 15 also embedded in the bracket and extending through the full thickness thereof. The pipe lengths 15 accommodate securing bolts 16 extending therethrough. The heads of the bolts are provided with protective concrete covers 17. The bolts 16 are threaded into nuts 18 embedded in the column 10. The nuts 18 are of extra length and are partly threaded on anchor bars 19 embedded in the column. Short anchor bars 18a embedded in the column are welded to the nuts. These bars resist the shear stress applied to the nuts by the bond between the bars and the concrete of the column.

A precast reinforced concrete girder 20 has upper and lower reinforcing bars 21 and 22 embedded therein connected by stirrups 23 extending around the bars and welded thereto. A length of angle bar 24 is disposed transversely of the girder at each end and is welded to the ends of the upper reinforcing bars 21. A notch 25 is formed in the upper face of the girder adjacent each end to permit the insertion of bolts 26 through holes drilled in the vertical flange of the angle bar 24. The bolts 26 are threaded into nuts 27 similar to the nuts 18. As in the case of the latter, the nuts 27 are partly threaded on anchor bars 28 and are welded to short anchor bars 27a embedded in the column. As shown in the drawing, there is clearance between the angle bar 24 and the side of the column to permit the bolts 26 to be turned home so as to tension the upper bars 21 of the girder. Struts 29 in the form of short bars are welded to the angle bar 24 and the ends of the lower bars 22 of the girders. The notch 25 may be filled with concrete after the girder has been placed on the bracket and secured thereto.

Pipe lengths 30 are embedded in the girder adjacent the ends thereof and are welded to the reinforcing bars 21 and 22. Bolts 31 inserted through the pipe lengths 30 are threaded into nuts 32 embedded in the bracket 13 and welded to the pipe lengths 15 thereof.

By reason of the means provided for securing the upper portion of the end of the girder 22 to the column, i. e., the anchor bar 24 and bolts 26, nuts 27 and bars 27a, deflection of the girder under load will develop a horizontal compression in the upper portion of the bracket 13. That is to say, as the girder is loaded, the end shown

in Figure 1 will tend to turn clockwise. This tendency will be resisted by the tension developed in the securing means just mentioned and a corresponding compressive force in the bracket transmitted from the pipe lengths 30, bolts 31 and pipe lengths 15, to the nuts 18 of the column. It will thus be apparent that, instead of being subject to a force tending to pull it away from the column, the bracket is actually forced against the column. The bracket, furthermore, shares the shear load on the girder with the bolts 26.

Figure 2 illustrates a modified form of column 35 having a bracket 36 cast integral therewith. The column has longitudinal reinforcing bars 37 and transverse reinforcing rods 38 similar to those of the column 10. A precast reinforced concrete girder 39 rests on the bracket 36. The girder has upper and lower reinforcing bars 40 and 41, the ends of which project beyond the end of the girder and are threaded. The column has nuts 42 welded to the bars 37 thereof. Studs 43 are threaded into the nuts 42. The studs preferably have left-hand threads on their protruding ends whereby the bars 41 may be secured thereto by nuts 44. When the girder has been secured to the column, the space between them may be filled with concrete.

The bracket 36 has reinforcing bars 45 embedded therein; pipe lengths 46 are also embedded in the bracket and are welded to the bars 45. Bolts 47 inserted through the pipe lengths 46 are threaded into nuts 48 embedded in the girder and welded to the lower reinforcing bars 41 thereof.

It will be apparent that the construction shown in Figure 2 serves in the manner already explained in connection with Figure 1 to develop horizontal compression in the bracket on deflection of the girder under load. In Figure 2 this compression is applied partly to the lower studs 43, the tension being carried by the upper studs.

Figure 3 shows a construction generally similar to that of Figure 2 with slight modification. The bars 40' and 41' of the girder 39' have their protruding ends welded to the ends of anchor bars 50 embedded in the column 35'. Sleeves 51 of thermal insulating material, such as asbestos, are disposed about the ends of the bars 40', 41' and 50 to prevent cracking of the concrete of the girder and column on heating of the bars incident to welding. The upper corner of the bracket 36' of the column 35' is beveled as at 52 for engagement by a shoulder 53 formed on the lower face of the girder 49' adjacent the end thereof. This shoulder transmits to the bracket a portion of the compression developed on loading the girder, the remainder of the compression being transmitted from the lower bars 41' to the lower anchor bars 50, the tension being sustained by the upper anchor bars 50.

It will be apparent from the foregoing description and explanation that the construction of my invention has many advantages over the previous practice according to which the bracket securing means was relied on exclusively to withstand the tension resulting from the loading of the girder. The invention permits the bracket

securing means to be designed principally from the standpoint of carrying the shear load since there is no tension in the upper portion of the bracket but actually a heavy compression tending to hold it against the column. The upper portion of the end of the girder may be readily secured to the column in any one of several different ways, as shown in the drawings and fully described above.

10 In the case of the separately formed brackets shown in Figure 1, the construction of my invention tends to increase the friction between the abutting faces of the bracket of the column. In the case of the integral brackets, the construction avoids the tendency toward splitting of the bracket under the load of the girder. In all cases the construction provides a rigid connection between the column, girder and bracket. The bars of the girder are placed under tension in all cases; in Figure 1 by turning up the bolts; in Figure 2 by turning up the nuts; and in Figure 3 by the shrinkage of the weld or cooling. This tension gives continuous beam action instead of simple beam action. The tension existing in the bars of the girder, furthermore, tends to force the bracket against the column.

Although I have illustrated several forms in which the invention may be provided, it will be understood that changes in the details of the construction may be made without departing from the spirit of the invention or the scope of the appended claim.

I claim:

35 A building construction comprising a plurality of precast concrete members including a support member and a bracket member and a beam member resting on the bracket member, two hollow metal members embedded in the bracket member, a tie projecting from the support member 40 entering one of the metal members and a tie projecting from the beam member entering the second metal member, the two hollow metal members being connected together.

ALBERT HENDERSON.
